United States Patent Office.

GARRETTSON SMITH AND HENRY BROWN, OF PHILADELPHIA, PENNSYLVANIA, ASSIGNORS
TO DAVID L. BARTLETT AND H. W. ROBBINS, OF BALTIMORE, MARYLAND.

Design No. 2,810, dated October 22, 1867.

DESIGN FOR A COOK'S STOVE.

The Schedule referred to in these Letters Patent and making part of the same.

TO ALL WHOM IT MAY CONCERN:

Be it known that we, GARRETTSON SMITH and HENRY BROWN, of the city and county of Philadelphia, in the state of Pennsylvania, have originated and designed new and ornamental Patterns and Configurations for the Doors, Plates, and Panels of a Cook-Stove, which are exactly and faithfully delineated in the accompanying photograph, forming a part of this specification, describing the same.

In the accompanying photographic view, showing in perspective the front and side of our newly-designed cook-stove, A represents an ornamental design for the large oven-doors upon the sides of the stove, consisting of an elliptical centre piece, crossed by a scroll, and surrounded by a border of beaded work, enlarged by scallops with indented division lines, radiating from the centre of the door-plate and terminating in outward points. B represents substantially the same design reduced and adapted to the small side and front doors of the stove, the scroll being omitted from the elliptical centre piece. C, ornamental scrolls upon the spaces at each end of the front plate of the stove.

We claim as our invention, and desire to secure by Letters Patent—

The configuration of the designs illustrated in the accompanying view and herein described, applied to the ornamentation of a cook-stove, as herein set forth.

GARRETTSON SMITH,
HENRY BROWN.
